BAG SEALING MACHINE

Charles T. Hayes, Richmond, Va., assignor to
 James River Paper Products, Inc., Richmond,
 Va., a corporation of Virginia

Application July 31, 1937, Serial No. 156,799

18 Claims. (Cl. 93—27)

To seal the end of a paper bag so that it will be impervious to leakage of gases and liquids requires more than the momentary pressure which can be applied to it in the interval between bags produced on a high-speed bag-forming machine. One object of the present invention is to provide a sealing machine having a high output combined with application of pressure for an adequate time to seal the bag perfectly.

10 A particular object is to provide a sealing machine which can take the output of a bag-forming machine and still apply to each bag pressure for a sufficient time to effect a perfect seal.

15 Another object of the invention is to provide a bag-sealing machine capable of reactivating thermoplastic adhesive and at the same time applying pressure to seal the bag.

Another object is to provide a mechanism for the transfer of bags from a bag-forming machine 20 to a sealing machine.

Another object is to provide a bag-sealing machine capable of applying a gradually increasing pressure to the parts of the bag to be sealed together.

25 Further objects will appear from the detailed description of the invention which follows. Reference will be made in this description to an illustrative form of the invention shown in the accompanying drawings, wherein

30 Fig. 1 is a side elevation of a bag-sealing machine and transfer mechanism in accordance with the invention, with parts broken away to reduce the size of the figure;

Fig. 2 is a vertical section on the line 2—2 of 35 Fig. 1;

Fig. 3 is a detail section on the line 3—3 of Fig. 2;

Fig. 4 is a detail section on the line 4—4 of Fig. 2;

40 Fig. 5 is a detail section on the line 5—5 of Fig. 2;

Fig. 6 is a perspective view of one portion of the conveyor and its controlling mechanism;

Fig. 7 is a central section of one end of the 45 conveyor and the transfer mechanism, taken parallel to the path of travel of the bag;

Fig. 8 is a perspective view of the transfer flap; and

Fig. 9 is a detail sectional view illustrating the 50 transfer mechanism and clamp in a different position from that shown in Fig. 7.

The machine illustrated in the drawings is designed to seal the ends of bags by means of thermoplastic adhesive previously coated on the bag 55 and hardened. An example of a bag particularly

adapted to be sealed on this machine is shown in Haskell Patent No. 1,983,291. The adhesive should be present in sufficient thickness to provide a body capable of flowing under the application of heat and pressure into the folds and corners of the bag.

The bag-sealing machine comprises an endless conveyor 2 travelling upon sprockets 4 and 6 mounted upon shafts 4a and 6a respectively, journaled in bearings 8 and 10. These bearings are 10 mounted upon a frame 12 and the bearings 10 can be adjusted longitudinally of the frame by a screw 14 and clamped in position by screws 16. The conveyor is formed of two chains 18 and 20 connected together at intervals by clamps 22, 15 which will presently be described in detail. The upper span of the conveyor is supported by rails 24 and the lower span by rails 26.

Each clamp comprises a lower jaw 28 and an upper jaw 30. The lower jaw is connected to 20 the chains 18 and 20 by bolts 32 which form extensions of two adjacent pins of the chains. The upper jaw is guided between cheeks 34 of the lower jaw and its vertical motion is limited by headed screws 36 which screw into the upper 25 jaw and are slidably guided in holes 38 of the lower jaw. Surrounding each screw 36 is a spring 40, these springs normally holding the jaws apart. The lower jaw is faced with a rubber cushion 42 held in a channel bar 44 attached by screws 46 30 to the lower jaw. The upper jaw is bored to receive a heating element 48, which receives current through wires 50 in a manner to be described presently. At the ends of the lower jaw 28 are 35 blocks 52 rabbeted to fit over the rails 24 so as to be guided thereby.

Standing up from the frame 12 are bridges 54 comprising upright legs 56 and crossbars 58. Cam rails 60 are mounted upon the legs 56 by screws 62 fitting through elongated slots 64 in 40 the cam rails and screwing into the legs 56. The heads of the screws 62 hold the cam rails 60 against lateral motion, but allow the rails to move up and down guided by the shanks of the screws. The cam rails rest upon rollers 66 journaled upon pins 68 projecting from the ends of the upper jaw 30 of each clamp 22. The cam rails 60 may be held up by springs (not shown) attached to them and also by the springs 40 of the clamps. Extending across the bridges 54 are 45 shafts 70, to which are fixed cams 72 acting against the upper side of cam rails 60. A hand-wheel 74 is fastened upon one shaft 70 and this shaft is connected by sprocket wheels 76, 78 and a chain 80 to the other shaft 70. Thus rotation 50 55

of the handwheel 74 causes the shafts 70 to turn in unison and the cams 72 to bear in unison against the cam rails 60. When the cams 72 are turned down the cam rails 60 press the upper jaws of the clamps 22 down against the lower jaws. When the cams 72 are turned up the cam rails release the upper jaws of the clamps and allow the springs 40 to separate them from the lower jaws. When the cams 72 are turned down 10 and the conveyor is travelling in counterclockwise direction, the clamps are open as they travel along the bottom and are closed as they are engaged by the downwardly turned ends 82 of the cam rails 60. It is just prior to the closure of the clamps at this point that the bags are fed in by a transfer mechanism to be described presently. If for any reason it is necessary to stop the travel of the conveyor the cam rails 60 can be raised immediately to allow the clamps to open and release the bags, so that they will not be charred by the heated clamps. The cams 72 are secured to shafts 70 by set screws 84 passing through their hubs 86. By adjusting the cams 72 on the right-hand shaft 70 of Fig. 1 so that they do not turn down quite so far as the cams on the left-hand shaft 70, the cam rails 60 will be set with a gradual slope, so that they will press the jaws of the clamps together harder and harder as the clamps travel toward the delivery end of the sealing machine. Thus at the start, when the adhesive is still hard, not so much pressure is applied as to crack the adhesive and perhaps rupture the paper, while after the adhesive has melted the pressure becomes sufficiently heavy to force the adhesive into the minutest cracks and folds of the bag. The rubber facing of the lower jaw enables the jaw to adapt itself to different thickness of paper at different parts of the bag.

The wires 50 leading to the heating element 48 of each clamp are connected to a brush box 88 having brushes 90 which bear against conductor bars 92 mounted upon insulating supporting bars 94 suspended by brackets 96 from the bottom of rails 24. Preferably the heating elements of all the clamps are connected together, as indicated by wires 98 of Fig. 6, so that it is only necessary for the conductor bars 92 to extend over a distance slightly longer than the space between two of the clamps. In this way the brush box 88 attached to each clamp will in turn take up the supply of electricity from the conductor bars to all the heating elements. The conductor bars and their support are curved away from the brush boxes at the right end to allow the brushes to feed on to the conductor bars smoothly.

The transfer of the bags from the bag-forming machine (not shown) to the bag sealing machine is accomplished by the mechanism shown in outline in Fig. 1 and in detail in Figs. 7, 8 and 9. A drum 100 corresponds to the bottom closing drum of the ordinary bag machine, but in this case it does not serve to seal the bottoms of the bags. The bottoms of the bags are tucked by tucker bars 102 on a drum 104 behind clamps 108 on the drum 100. The bags are drawn by the clamps past an idler roller 108 and there released from the clamps in the usual way. A band 110 travelling over drum 100 and idler rollers 112 and 114 conveys the bags to and partly around another drum 116. The drum 116 is rigidly connected to a gear 118 meshing with a gear 120 rigidly connected with sprocket wheel 4 of the bag-sealing machine, so that the roller 116 rotates with the same peripheral speed as the sprocket 4. The roller 116 is recessed at 122 and 124 to receive the

clamps 22 as they pass. Below the drum 116 is rotatably mounted a shaft 126 which carries the idler roller 112 loosely upon it and besides has fixed to it a transfer flap 128. This flap is arranged to swing from the dotted line position 128a to the full line position 128 through the action of a cam 130 fixed to the shaft 132 of drum 116. This cam bears against a roller 133 on a lever 134 which swings on a fixed pivot 136 and has connected to its lower end a link 138. The other end of link 138 is articulated to an arm 140 fixed to shaft 126. Thus for each half revolution of drum 116 the cam 130 swings the flap up to full line position and down to dotted line position. This swing is coordinated with the travel 15 of the clamp which is passing at the time so that just as the clamp reaches the proximal position shown in Fig. 7 the flap, which is moving somewhat more rapidly, swings up from the position shown in Fig. 9 and thrusts the projecting end of 20 the bag between the open jaws of the clamp. Shortly after, as the bag continues to move upward with the drum 116 and the clamp 22, the cam 82 engages the rollers 66 of the upper jaw of the clamp and presses the upper jaw down 25 against the end of the bag. The end of the bag being supplied with a hardened thermoplastic adhesive, as the heat and pressure continues, the thermoplastic melts and flows into a continuous body penetrating the smallest cracks and folds of 30 the bag end.

The drive for the drums 116 is derived from a gear 150 through an intermediate gear 152 meshing with gear 118. The drum 100 is driven by a gear 154 fixed to it and meshing with gear 150.

It will be seen that I have described a machine capable of taking bags from a bag-forming machine as fast as they are formed, holding them by clamps, which may be heated, for any desired length of time, depending upon the length of the 40 conveyor and cam rails 82, and finally releasing the bags as the clamps are opened at the end of the cam rails.

Having described my invention, I claim:—

1. In a bag sealing machine, an endless conveyor, a series of clamps on said conveyor, each comprising a pair of parallel jaws arranged transversely on said conveyor and having a limited relative movement to open and close the clamp, springs normally holding said jaws apart, means for closing said jaws and holding the same closed during a portion of the travel of said conveyor, and means for feeding a bag between each pair of jaws just prior to its closure.

2. In a bag sealing machine, an endless conveyor, a series of clamps on said conveyor, each comprising a pair of parallel jaws arranged transversely on said conveyor and having a limited relative movement to open and close the clamp, springs normally holding said jaws apart, cam bars mounted adjacent said conveyor in position to engage the jaws of said clamps in their travel and to hold the jaws closed during a portion of their travel, and means for feeding a bag between each pair of jaws just prior to its closure.

3. In a bag sealing machine, an endless conveyor, a series of clamps on said conveyor, each comprising a pair of parallel jaws arranged transversely on said conveyor and having a limited relative movement to open and close the clamp, springs normally holding said jaws apart, cam bars mounted adjacent said conveyor in position to engage the jaws of said clamps in their travel and to hold the jaws closed during a portion of their travel, said cam bars having a gradual slope 75

so as to increase their pressure on said clamps gradually, and means for feeding a bag between each pair of jaws just prior to its closure.

4. In a bag sealing machine, an endless conveyor, a series of clamps on said conveyor, each comprising a pair of parallel jaws arranged transversely on said conveyor and having a limited relative movement to open and close the clamp, springs normally holding said jaws apart, cam bars mounted adjacent said conveyor in position to engage the jaws of said clamps in their travel and to hold the jaws closed during a portion of their travel, said cam bars being independently adjustable at their opposite ends in order to vary their position with respect to the path of travel of said clamps, and means for feeding a bag between each pair of jaws just prior to its closure.

5. In a bag sealing machine, an endless conveyor, a series of clamps on said conveyor, each comprising a pair of parallel jaws arranged transversely on said conveyor and having a limited relative movement to open and close the clamp, springs normally holding said jaws apart, cam bars mounted adjacent said conveyor so as to be movable toward and away from the conveyor, means for so moving said cam bars; said cam bars, when nearest to said conveyor, being adapted to engage the jaws of said clamps in their travel and to hold the jaws closed during a portion of their travel, means for heating said clamps, and means for feeding a bag between each pair of jaws just prior to its closure.

6. In a bag sealing machine, an endless conveyor, a series of clamps on said conveyor, each comprising a pair of parallel jaws arranged transversely on said conveyor and having a limited relative movement to open and close the clamp, springs normally holding said jaws apart, cam bars mounted adjacent said conveyor so as to be movable toward and away from the conveyor, a plurality of cams adapted to bear at different points upon said cam bars to move the same, means for operating said cams simultaneously; said cam bars, when nearest to said conveyor, being adapted to engage the jaws of said clamps in their travel and to hold the jaws closed during a portion of their travel; means for heating said clamps, and means for feeding a bag between each pair of jaws just prior to its closure.

7. In a bag sealing machine, a conveyor, a series of clamps on said conveyor, electric heating elements in said clamps, slide conductors mounted parallel to the conveyor, brushes travelling on said conductors and connected with said heating elements, means for opening and closing said clamps, and means for feeding bags to said clamps just prior to their closure.

8. In a bag sealing machine, a conveyor, a series of clamps on said conveyor, electric heating elements in said clamps, conductors connecting said heating elements together, slide conductors mounted parallel to the conveyor, a plurality of sets of brushes mounted at spaced points on said conveyor and bearing on said slide conductors, means connecting said brushes with said heating elements, said slide conductors being shorter than the length of the conveyor, but longer than the distance between two sets of brushes, means for opening and closing said clamps, and means for feeding bags to said clamps just prior to their closure.

9. In a bag sealing machine, an endless conveyor, a series of clamps mounted transversely on said conveyor, each clamp comprising a pair of jaws, one of said jaws being composed of metal

and containing a heating element, the other jaw having a yielding face, means whereby said jaws are held apart during a portion of the conveyor travel and are held closed during another portion of the conveyor travel, and means for feeding bags to said clamps just prior to their closure.

10. The combination with a bag sealing machine comprising a travelling conveyor having clamps thereon to grasp and seal the bags, of a drum adjacent said conveyor, a conveyor band cooperating with said drum to feed the bags toward said clamps and a guide flap adapted to engage each bag as it emerges from said conveyor band to guide it into one of said clamps.

11. The combination with a bag sealing machine comprising a travelling conveyor having clamps thereon to grasp and seal the bags, of a drum adjacent said conveyor, a conveyor band cooperating with said drum to feed the bags toward said clamps and a pivoted guide flap adapted to engage each bag as it emerges from said conveyor band, said guide flap normally standing out of the path of said clamps, and means to swing said guide flap in behind each clamp as it passes to guide the bag into the clamp.

12. In a bag sealing machine, an endless conveyor comprising a pair of continuous flexible members joined at intervals by rigid cross members, each cross member having associated with it a bar normally held apart from said cross member by springs, but movable into contact with said cross member to act as a clamp for clamping bags to be sealed, and means for moving said bar into contact with said cross member at a certain point in the travel of said conveyor.

13. In a bag sealing machine, an endless conveyor comprising a pair of continuous flexible members joined at intervals by rigid cross members, each cross member having associated with it a bar normally held apart from said cross member by springs, but movable into contact with said cross member to act as a clamp for clamping bags to be sealed, stationary guide bars on which said cross members travel, and cam bars adapted to be engaged by said bars in their travel to force the same into contact with said cross members and to maintain said contact during a predetermined length of travel of said conveyor.

14. In a machine for sealing bags by thermoplastic adhesive previously hardened on the bag material, clamping means having opposed pressure surfaces, means for heating at least one of said pressure surfaces, means for feeding a bag between said pressure surfaces, and means for pressing said surfaces together with a pressure which increases gradually as the adhesive melts and reaches its full force only when the adhesive has entirely melted.

15. In a machine for sealing bags by thermoplastic adhesive previously hardened on the bag material, clamping means comprising a yielding jaw and a metallic jaw, means for heating the metallic jaw, means for feeding a bag between said jaws, and means operating in synchronism with said feeding means for pressing said jaws together, first with a light pressure and then with a gradually increasing pressure.

16. For use in combination with a bag machine adapted to convert a continuously travelling sheet of paper into a tube and to sever the tube into bag lengths, a bottom sealing mechanism adapted to receive the bag lengths as they are delivered from the bag machine and to reactivate a thermoplastic adhesive previously applied to the bottom of the bag length and to seal the bag bottom by pres-

- sure, said mechanism comprising an endless conveyor, means for moving said conveyor in synchronism with the bag machine, a series of clamps on said conveyor adapted to receive the bag lengths successively as they are delivered from the bag machine, means for heating said clamps, and means for applying a gradually increasing pressure to each clamp after it receives a bag length.
- 10 17. In a bag sealing machine, a conveyor, a series of clamps on said conveyor, electric resistance elements mounted in heat transmitting relation on said clamps, means for transmitting electrical energy to said resistance elements from a stationary source, means for opening and clos-
- 15

ing said clamps, and means for feeding bags to said clamps just prior to their closure.

18. For use in combination with a bag machine adapted to convert a continuously travelling sheet of paper into a tube and to sever the tube into bag lengths, a bottom sealing mechanism adapted to receive the bag lengths as they are delivered from the bag machine comprising an endless conveyor, a series of clamps on said conveyor, a pivoted flap adapted to engage each bag length as it is delivered from the bag machine, said flap normally standing out of the path of said clamps, and means to swing said guide flap in behind each clamp as it passes, to guide the bag into the clamp.

CHARLES T. HAYES.
